UNITED STATES PATENT OFFICE.

CHAUNCY BEWEL RUBY, OF LE MARS, IOWA.

WIRE-WINDER.

1,086,225.

Specification of Letters Patent.

Patented Feb. 3, 1914.

Application filed April 21, 1913. Serial No. 762,518.

To all whom it may concern:

Be it known that I, CHAUNCY B. RUBY, a citizen of the United States, and a resident of Le Mars, in the county of Plymouth and State of Iowa, have made certain new and useful Improvements in Wire-Winders, of which the following is a specification.

My invention is an improvement in wire winders, and has for its object to provide a device of the character specified, wherein means is provided for holding and rotating a reel, together with means, capable of being operated from a point adjacent to the reel, for constraining the wire to wind in uniform layers upon the reel.

In the drawings: Figure 1 is a perspective view of the improved winder, Fig. 2 is a longitudinal vertical section, Fig. 3 is a partial front view with parts in section, and

Fig. 4 is a section on the line 4—4 of Fig. 3.

The present embodiment of the invention comprises a frame composed of longitudinal laterally spaced parallel bars 1, connected at one end by a cross bar 2, and at the other end of each of the said longitudinal bars is arranged an upright 3, each of the said uprights being inclined toward its upper end, and braced against the adjacent longitudinal bar by an inclined brace 4, each brace being connected to the longitudinal bar and the upright.

Diagonal braces 5 are arranged between the longitudinal bars, between the cross bar 2 and the upright 3, the said diagonal bars 5 crossing each other between the longitudinal bars. Each of the uprights is also braced against the opposite longitudinal bar, by means of an inclined brace 6, the said braces crossing intermediate their ends, and a cross bar 7 connects the uprights near their lower ends, the said cross bar being arranged with its wide dimension vertical.

A shaft 8 is journaled in the upper ends of the uprights, and a crank 9 is connected with one end of the shaft outside the adjacent upright. A spool or sleeve 10 is arranged on the shaft at the end remote from the crank, the said spool or sleeve being held in place by a set screw 11, threaded through the spool into engagement with the shaft. A pulley or band wheel 12 is arranged on the shaft at the end adjacent to the crank, and the said wheel is provided with an integral cross head 13, the said cross head being diametrical to the pulley

and shaft 8, and having at each end a lateral inwardly extending spur or prong 14.

The bearing for the shaft 8 in the upright adjacent to the crank 9 is an open bearing, as shown more particularly in Fig. 3, and a hasp 15 is connected to the upright below the bearing by means of a hinge leaf 16, the said hasp being hinged to the leaf, and the leaf is secured to the upright. A staple 17 is connected with the upright above the bearing for engagement by the hasp, and it will be evident that when the hasp is turned down upon the hinge leaf the adjacent end of the shaft may be readily disengaged from the bearing, and when the said end is disengaged from the bearing, the opposite end may be slipped out from its bearing.

The reel 18 for holding the wire 19 is of usual form, and is arranged on the shaft when the shaft has been removed from its bearing. The spool 10 is then removed by loosening the set screw 11, after which the reel is placed on the shaft and pressed toward the cross head 13, to cause the lugs or spurs 14 thereof to enter the material of the end of the reel. The spool or sleeve 10 is then adjusted into engagement with the opposite end of the reel, and secured in place by the set screw, after which the shaft is replaced in its bearings. The reel is now locked to the shaft, so that when the crank 9 is turned, the reel will be rotated to wind up the wire. A guide 20 of funnel or frustoconical shape is provided for the wire, the guide being arranged with its small end toward the shaft, so that the wire to be wound enters the large end of the guide. The said guide is secured to one of the portions 21 of an angle bar, and the other portion 22 of the said bar is connected to the upper end of the upper section 23 of a telescoping standard, by means of a bolt 24. The said section 23 of the standard is provided with a series of spaced longitudinal openings 25.

The lower section of the standard is formed by an arm 26 on one end of a rod 27 arranged in a manner to be presently described, the said arm 26 having at its free end an angular threaded lug 28, which is adapted to be passed through one of the openings 25, and to be engaged by a nut 29 to hold the sections of the standard in adjusted position. At its lower end the section 23 is provided with a lateral perforate lug 30 through which the arm 26 passes, and

the said arm passes also through a slot 31 extending longitudinally of the cross bar 2.

A bearing section 32 is connected with the cross bar below the slot, to support the 5 main portion 27 of the rod, and at its rear end, the rod is supported by another bearing section 33 connected with the lower edge of the cross bar 7. At its rear end, the rod is provided with an angular upstanding 10 arm 34, having secured thereto a handle 35 preferably of wood, and of cylindrical form, as shown. The said handle stands in position to be grasped by the operator turning the crank, to oscillate the rod 27, to 15 swing the guide 20 longitudinally of the shaft 8. An arch bar 36 is provided at one end with a bearing 37 engaged by a pin 38 in the upright 3 adjacent to the crank 9, and at its opposite end the arch bar has 20 a perforate radial lug 39 to which is connected a handle 40, by means of a bolt 40^a passing through the handle, and the perforation of the lug.

In operation, the reel 18 having been 25 placed on the shaft as desired, the end of the wire is passed through the guide 20, and is secured to the reel in any desired or usual manner. The shaft 8 is now rotated by means of the crank 9, and as the shaft 30 rotates, the wire is wound thereon, passing through the guide 20. The said guide is adjusted vertically, by means of the connection between the arm 26 and the bar 23, so that the small opening of the guide is at approximately the level of the lowermost portion of the reel. As the wire winds on the 35 reel the rod 27 is oscillated by means of the handle 35, to cause the guide 20 to swing slowly longitudinally of the shaft. The 40 said guide is moved at such speed, that the coils of the wire will lay alongside each other in close relation, yet not sufficiently close to overlap. The arch bar 36 and the handle 40 constitute a brake for coöperating 45 with the pulley 12, as indicated in dotted lines in Fig. 2. The arch bar is shaped to approximately fit the pulley. The guide 20 is provided with a longitudinal slot 41 at one side, to permit the wire to be inserted in 50 the holder intermediate the ends of the wire. The front ends of the bars 1 are also beveled or inclined, as indicated at 42, to permit the frame to be drawn along the ground as a sled, or if desired an axle 43 55 may be arranged beneath the front ends of the said bars, the axle having wheels 44 at

the ends thereof. The axle is supported in notches in bearing plates 45, pivoted to the bars, as indicated at 46, and normally held in engagement with the axle by means of 60 hooks 47, the said hooks being pivoted also to the bars 1. When it is desired to remove the wheels, the hooks 47 are released from the plates, permitting the said plates to swing downwardly, after which the axle 65 may be disengaged from the notches or recesses in the edges of the said plates.

The device is especially adapted for winding fence wire, when taking down a fence. When so used, the frame may be moved as a 70 sled or with the wheels, winding up the wire as the device moves along the fence.

I claim:

1. A device of the character specified, comprising a main frame, uprights at one 75 end of the main frame, each upright having a bearing and the bearing of one upright being an open bearing, a shaft journaled in the bearings and provided at the end adjacent to the open bearing with a crank, releasable means for holding the shaft in the open bearing, a wheel on the shaft at the open bearing, a cross head rigid with the wheel and the shaft and having at its end inwardly extending spurs or lugs for engaging the material of a reel, a sleeve slidable 80 on the shaft for engaging the opposite end of the reel, and means for securing the sleeve in adjusted position.

2. A device of the character specified, 90 comprising a main frame, uprights at one end of the frame and provided with bearings for receiving the reel holding shaft, a shaft in the bearings and having means for engaging the reel, and means on the frame 95 for guiding the wire, said means comprising a rod mounted to oscillate and arranged longitudinally of the main frame, a handle extending upwardly from the inner end of the rod adjacent to the reel holding shaft 100 for oscillating the rod, said rod having an upwardly extending arm at the opposite end, a substantially tubular guide for the wire, said guide having a slot in its side wall for permitting the entrance of the wire, 105 an arm secured to the guide, and an adjustable connection between the said arm and the arm of the rod.
